LEWIS C. BAYLES, OF EASTON, PENNSYLVANIA, AND HERBERT T. ABRAMS, OF ORANGE, NEW JERSEY, ASSIGNEES TO INGERSOLL-RAND COMPANY, OF JERSEY CITY, NEW JERSEY, A CORPORATION OF NEW JERSEY.

FLUID-PRESSURE PUMPING APPARATUS.

Application filed February 28, 1924. Serial No. 695,621.

To all whom it may concern:

Be it known that we, LEWIS C. BAYLES, a citizen of the United States, and a resident of Easton, county of Northampton, and State of Pennsylvania, and HERBERT T. ABRAMS, a citizen of the United States, and a resident of Orange, county of Essex, and State of New Jersey, have invented a certain Fluid-Pressure Pumping Apparatus, of which the following is a specification accompanied by drawings.

This invention relates to fluid pressure pumping apparatus, but more particularly to apparatus of this type for automatically and intermittently discharging the liquid from a deep well in accordance with the rise of liquid in the well.

Great difficulty is experienced in economically and efficiently pumping the liquid from a depleted or nearly exhausted oil well for instance. Because of the great depth, two-thousand feet or more for instance, and the comparatively small amount of oil which is available for recovery, at any one time, a reciprocating pump is expensive and impracticable. When a certain amount of oil is recovered, the pump must be stopped until sufficient oil has flowed into the well again to enable the pump to be used and this may take considerable time.

Furthermore, pumping apparatus of various kinds located in the bottom of the well involving valves forming component parts of the pump, are unsatisfactory because the valves are apt to get out of order or become clogged with mud or other foreign matter.

The object of the present invention is to enable the liquid in a nearly exhausted well to be readily and economically recovered by means of fluid pressure pumping apparatus which is simple and cheap to construct, and is valveless in so far as the parts at the bottom of the well are concerned.

Another object of the invention is to enable such a well to be automatically discharged by fluid pressure from time to time when the liquid has risen in the well to a given point. After each discharge the main fluid pressure supply is stopped or cut off and is not used again until the proper amount of liquid has flowed into the well. The apparatus does not require watching

or hand control but is entirely automatic and dependent for operation on the back pressure created in a casing forming a 55 pump chamber adapted to be located near the bottom of the well.

The apparatus is shown in one of its preferred forms in the accompanying drawing, in which,

Figure 1 is a diagrammatic longitudinal sectional elevation, broken in its length, of a deep well having our apparatus applied thereto,

Figure 2 is an enlarged sectional elevation 65 of the controlling valve in closed position,

Figure 3 is a similar view of the valve in open position, and

Figure 4 is a similar view with the valve closed, but certain parts in a different position from those indicated in Figure 3.

Referring to the drawings, the deep well A which may be an oil well, is assumed to be greatly depleted or nearly exhausted of its oil and for the purpose of recovering this 75 oil, a casing B forming a pump chamber is adapted to be located in the well near the bottom of the well and below the level C of the liquid to which the oil will rise in the well, after a given period of time.

The casing B is preferably provided with the upper head D and the lower head E, and a filling pipe F as shown extends from a point G within the pump chamber near the upper head D, down through the lower head 85 E to a point H near the bottom of the well.

A discharge pipe J extends from a point K within the pump chamber near the bottom head E, through the upper head D to the surface of the ground L and is preferably provided with a down turned end O discharging into a tank or hopper P. This discharge pipe J is preferably provided with a vent Q within the pump chamber near the upper head D, through which pressure fluid 95 as compressed air, entering the pump chamber may escape to atmosphere until the vent Q is closed by the liquid rising in the pump chamber from the well through the filling pipe F.

A main fluid pressure supply pipe R extends from the surface of the ground to the pump chamber and terminates substantially at the point S above the height of the upper

end G of the filling pipe. As the liquid in the well rises through the filling pipe F and fills the pump chamber, the air above the liquid will escape through the vent Q until said vent Q is closed by the liquid. The back pressure then created in the supply pipe R is utilized to control the opening of the controlling means T connected to the supply pipe above ground, and automatically supply fluid under line pressure from the supply line U to the pump chamber to discharge the liquid. This controlling means T preferably in the form of a valve, includes means for continuously permitting leakage of pressure fluid down the supply pipe R to the pump chamber until discharge takes place, and in this instance, means are provided controlled by the liquid discharged for cutting off the main pressure fluid supply from the main line U to the pump chamber, so that the apparatus is in readiness to permit the filling of the pump chamber again with oil or other liquid, and the well will be intermittently and automatically discharged.

25 The controlling apparatus indicated by the character T comprises a valve casing V to which the main supply line U is connected and to which the supply pipe R is also connected. A main valve W is located in the casing V having the head X controlling the passage of fluid from the main line U to the supply pipe R. The main valve W is preferably spring pressed and is normally held in closed position, as indicated in Figure 2, by means of the spring Y underneath the adjustable cap Z having the vent a.

The main valve W is preferably controlled by the auxiliary valve b shown in the form of a cylindrical pin, in the end of the valve casing V and provided with a groove c controlling communication between the by-pass d and the head e of the main valve. The auxiliary valve is also provided with a passage f extending from one end of the valve g to an opening h at the side of the other end of the valve, so that as the auxiliary valve is moved up and down, the space beneath the head e of the main valve W may be vented to atmosphere.

50 In this instance a lever j is pivoted at the point k to the valve casing V and is also pivotally connected at the point o to the auxiliary valve b. A retracting spring p normally holds the lever j retracted against the valve casing V, as shown in Figure 2, and a bucket q or other suitable receptacle is hung from the outer end r of the lever, and located in a position adjacent to the upper end of the discharge pipe J so that some of the liquid discharged will pass into the bucket through the small pipe s and when sufficient liquid has weighted the bucket, the tension of the spring p will be over-come and the lever j will assume the position indicated in Figure 4. A stop in the form of

a hook t is preferably provided on the lever j to limit its movement.

We are not to be understood as limiting the invention to the particular form of controlling valve illustrated in the drawing, but a suitable valve and mechanism is shown for the purpose of the invention and other equivalent controlling devices could be constructed by those skilled in the art without departing from the spirit of our invention.

In this instance, the controlling valve mechanism is so constructed that constant leakage of air under pressure is permitted on the main line U down through the supply pipe R to the pump chamber. To accomplish this object, the valve W is purposely made a loose fit in the valve casing V so that there will always be leakage past the head X to the pipe R and also past the head e through the by-pass d to the pipe R when the valve is in the position indicated in Figure 2. This constant leakage of air or pressure fluid passes to atmosphere through the vent hole Q in the discharge pipe J until said hole is closed.

In the operation of the apparatus, the oil entering the well will rise in the filling pipe F and pass into the pump chamber in which the level will rise until the vent Q is closed. If it be assumed that the pump casing B is located a given distance below the level of the liquid to which the oil will rise in the well, back pressure will be created in the supply pipe R due to the height of the liquid in the well above the vent Q augmented by the leakage referred to and the parts of the controlling mechanism are so adjusted that this back pressure will be sufficient, when acting upon the head e of the main valve W, to which the pressure is communicated through the by-pass d, to raise the main valve W against the spring Y to the position indicated in Figure 3. Pressure fluid from the main line U will then be admitted to the pump chamber and the oil within the pump chamber will be discharged up through the discharge pipe J to the surface of the ground thus emptying the chamber.

The function of the bucket or receptacle q, is to pull down the controlling lever j when sufficient oil has entered the bucket and move the lever to the position indicated in Figure 4, in which case the space under the head e of the main valve W will be vented to atmosphere through the passage f and the spring Y will close the main valve and shut off the pressure fluid supply to the pump chamber. An aperture u is provided in the bottom of the bucket q to permit the oil to leak out and when sufficient oil has leaked from the bucket, the spring p will restore the lever to its initial position, as indicated in Figure 2 so that the controlling mechanism is ready for automatic operation when

the pump chamber has again filled with oil.

It is to be understood that in Figure 1, the controlling valve is assumed to be open, having been opened by the back pressure and

- 5 the chamber is in the process of being discharged, because the level of the liquid *v* in the chamber is shown about half way of the height of the chamber and the oil is being forced out of the discharge pipe *J*, but has
- 10 not as yet reached the top of the pipe at the surface of the ground. The pressure in the pump chamber has also lowered the oil in the filling pipe *F* to the point *w* to a level below that in the well, but the leakage and
- 15 arrangement of parts should be such that the oil will not be forced out of the filling pipe *F*, although a check valve could be used in the top of the filling pipe if desired to prevent oil being forced out of this pipe.

20 We claim:

- 1. Fluid pressure pumping apparatus for automatically discharging liquid from a well in accordance with the rise of liquid in the well, comprising a casing located in the 25 well into which casing the liquid is permitted to enter, means controlled by the back pressure in the casing for automatically discharging the casing by main pressure fluid, and means controlled by the liquid discharged for cutting off the main pressure fluid.

- 2. Fluid pressure pumping apparatus for automatically discharging liquid from a well in accordance with the rise of liquid in the well, comprising a casing located in the 35 well into which casing constant leakage of pressure fluid is permitted from a main source of supply, means for permitting the liquid in the well to enter said casing, means controlled by the back pressure in the casing for automatically discharging the casing by pressure fluid, and means controlled by the liquid discharged for cutting off the main pressure fluid.

- 45 3. Fluid pressure pumping apparatus for wells, comprising a casing forming a pump chamber adapted to be located in the well, a filling pipe extending from a point near the top of the chamber to a point below the bottom of the chamber for permitting liquid to enter the pump chamber, a discharge pipe extending from a point near the bottom of the chamber to the surface of the ground, a main fluid pressure supply pipe extending 50 from above ground to the pump chamber and terminating above the height of the upper end of the filling pipe, controlling means for the main fluid pressure supply pipe controlled by the back pressure in the pump chamber for automatically discharging the pump chamber, and means controlled by the liquid discharged for cutting off the main pressure fluid.

- 60 4. Fluid pressure pumping apparatus for wells, comprising a casing forming a pump

chamber adapted to be located in the well, a filling pipe extending from a point near the top of the chamber to a point below the bottom of the chamber for permitting liquid to enter the pump chamber, a discharge pipe 70 extending from a point near the bottom of the chamber to the surface of the ground, a main fluid pressure supply pipe extending from above ground to the pump chamber and terminating above the height of the upper end of the filling pipe, controlling means for the main fluid pressure supply pipe controlled by the back pressure in the pump chamber for automatically discharging the pump chamber, including means for constantly permitting leakage of pressure fluid from the main supply to the pump chamber until discharge takes place, and means controlled by the liquid discharged for cutting off the main pressure fluid.

5. Fluid pressure pumping apparatus for wells, comprising a casing forming a pump chamber adapted to be located in the well, a filling pipe extending from a point near the top of the chamber to a point below the bottom of the chamber for permitting liquid to enter the pump chamber, a discharge pipe extending from a point near the bottom of the chamber to the surface of the ground, a main fluid pressure supply pipe extending from above ground to the pump chamber and terminating above the height of the upper end of the filling pipe, controlling means for the main fluid pressure supply pipe caused to be opened by the back pressure in the pump chamber for automatically discharging the pump chamber and means controlled by the liquid discharged for closing said controlling means, and cutting off the main pressure fluid, whereby the well is intermittently discharged.

6. Fluid pressure pumping apparatus for automatically discharging liquid from a depleted well in accordance with the rise of liquid in the well, comprising a casing forming a pump chamber having end heads and adapted to be located in the well below the level of the liquid, a filling pipe extending from a point within the pump chamber near the upper head, through the lower head to a point below the bottom of the casing, a discharge pipe extending from a point within the pump chamber near the bottom head, through the upper head to the surface of the ground, and having a vent within the chamber near the upper head, a main fluid pressure supply pipe extending from the surface of the ground to the pump chamber and terminating above the height of the upper end of the filling pipe, and controlling means connected to the supply pipe above ground and controlled by the back pressure created in the pump chamber when the vent in the discharge pipe is closed by the rising liquid for automatically supplying fluid.

under line pressure to the pump chamber to discharge the liquid, including means for constantly permitting leakage of pressure fluid from the supply pipe to the pump chamber until discharge takes place, and means controlled by the liquid discharged for cutting off the main pressure fluid sup-

ply to the pump chamber, whereby the well is intermittently discharged.

In testimony whereof we have signed this 10 specification.

LEWIS C. BAYLES.

HERBERT T. ABRAMS.
